UNITED STATES PATENT OFFICE.

GEORGE B. VON BODEN, OF SACRAMENTO, AND EDWIN F. INGLES, OF SAN FRANCISCO, CALIFORNIA.

OIL-BURNER.

SPECIFICATION forming part of Letters Patent No. 760,826, dated May 24, 1904.

Application filed January 27, 1904. Serial No. 190,804. (No model.)

To all whom it may concern:

Be it known that we, GEORGE B. VON BODEN, a resident of Sacramento, county of Sacramento, and EDWIN F. INGLES, a resident of the city and county of San Francisco, State of California, citizens of the United States, have invented new and useful Improvements in Oil-Burners, of which the following is a specification.

10 Our invention relates to an atomizer or burner for use in the utilization of petroleum or other liquid or pulverized fuel to produce steam or generate heat for any purposes; but it is designed particularly to generate steam 15 for locomotive, stationary, and marine boilers.

It consists of a metal conduit having separate passages, one or more to convey the fuel and one or more to convey the steam, compressed air, gas, or other vapor, or combination of the same, to be used in spraying or spreading the fuel or supplying oxygen to the fire.

The particular feature of this device consists in combining the fuel and vapor on or 25 above a lip or plane having a smooth or irregular surface projecting in front of the oil and steam discharge and slightly below the latter for the purpose of more thoroughly mixing the discharge or controlling its movement before passing into the fire.

Our invention also comprises details of construction which will be more fully explained by reference to the accompanying drawings, in which—

35 Figure 1 is a plan view. Fig. 2 is a longitudinal vertical section. Fig. 3 is a transverse section. Fig. 4 is a view showing smooth surface on lip.

It is the object of our invention to provide 40 a device for the combustion of oil or petroleum product in which we are enabled by the relative arrangement of the oil and steam discharge openings and of a substantially parallel smooth or corrugated lip projecting and 45 forming a shelf slightly below the steam-discharge to more thoroughly combine the steam with the fuel and vapor and to more finely atomize the oil, so that we produce a milder flame at a lower velocity and reduce

the flash and noise, as well as giving a better 50 distribution of the heat.

As shown in the drawings, the conduit A has oil and steam passages 2 and 3, the oil-passage located above the steam-passage, and at the rear end of the conduit each of these 55 passages is screw-threaded or otherwise constructed for the connection, respectively, of an oil and a steam supply pipe. The steam and oil flow through the passages 2 and 3 substantially parallel, the oil-passage above 60 the steam-passage.

The oil-conduit has a substantially rectangular opening 3' at the front, said opening having its greatest length horizontal and its transverse depth vertical. The upper part 65 or roof of this conduit is curved downwardly, as shown at 4, and the floor is similarly curved, as shown at 5.

The steam-conduit has a narrow and transversely-elongated slit 6, through which steam 70 is discharged, and the oil flowing easily over the curved front 5 meets the jet of steam at this point and is finely atomized thereby.

7 is a lip or plane extending forward from the steam-discharge opening slightly below 75 and substantially parallel with the plane of discharge of said opening. This lip or surface may be smooth, transversely corrugated, or otherwise formed with an irregular surface. In the present case we have shown the 80 corrugations as extending in straight lines transverse to the plane of discharge, and the front edge of the lip is segmentally curved, as shown at 8.

In order to confine the discharge and prevent its flowing off the sides, we have shown a raised extension 9 upon each side of the lip, this extension having a height approximating the lower edge of the steam-discharge slit.

By the peculiar arrangement of the steam 90 and oil discharge passages and the extension or lip we are enabled more thoroughly to atomize and pulverize the oil and accomplish its intimate mixture with the steam or equivalent elastic fluid discharged under pressure. This 95 result is more perfectly accomplished by reason of the broad transversedischarge-openings and the peculiar shape of the oil-discharge,

which causes it to flow gently down upon the constantly-discharging sheet of steam, the lip or table extending to the front having a breadth substantially equal to that of the discharge-sheets of steam and oil and being located slightly below the plane of the steam-discharge, with the curved front and the side walls or extensions to prevent the oil from throwing off the sides of the lip.

10 Having thus described our invention, what we claim, and desire to secure by Letters Patent, is—

1. An oil-burner having in combination a plurality of substantially parallel conduits for oil and steam said conduits having their discharge ends terminating in substantially the same vertical plane and said oil-discharge end having its upper and lower edges curved downward to direct the discharging oil across the discharge end of the steam-conduit, and an uncovered lip or table extending to the front of the steam and oil discharge and made imperforate and with its top surface horizontal and substantially parallel with the plane of the steam-discharge and slightly therebelow.

2. An oil-burner having in combination a plurality of conduits for oil and steam, the latter located above the former and each having a broad horizontally-disposed discharge-slit at the front end, and said oil-conduit having a down-curved upper and lower portion at said front end, and an imperforate lip or table having a horizontal upper surface parallel with and slightly below the steam-discharge, and having side walls and a transversely-curved front edge.

3. An oil-burner comprising a metal conduit having substantially parallel horizontal steam and oil passages, the latter located above the former, and means for supplying steam and oil at the rear of said passages, an imperforate

extension lip or table projecting forwardly from the lower part of the conduit, a broad horizontal steam-discharge slit located slightly above the plane of the table, a similarly-shaped oil-discharge passage, said passage having its upper and lower edges curved downwardly to allow the oil in its flow to be impinged and atomized by the steam in its passage across the lip or table.

4. The combination in an oil-burner of a metal conduit having substantially parallel steam and oil passages with supply connections at the rear, horizontally-broad and vertically-narrow discharge-slits at the front, the oil-discharge slit being curved to cause the oil to impinge upon the horizontally-discharging steam from the slit below, a lip or table having transverse corrugations formed in its surface, said lip being located slightly below the plane of steam-discharge.

5. An oil-burner comprising a metal conduit having wide rectangular substantially parallel oil and steam passages with supply connections at the rear, a substantially horizontal lip or table projecting from the lower part of the conduit, said lip having a transversely-corrugated surface, side retaining-walls and a segmentally-curved front edge, a horizontally-wide steam-discharge slit slightly above the surface of said table, and a similarly-shaped downwardly-curved oil-discharge slit located above the steam-discharge.

In testimony whereof we have hereunto set our hands in presence of two subscribing witnesses.
